UNITED STATES PATENT OFFICE.

MANUEL D. AVILLAR, OF NEW YORK, N. Y.

MACHINE FOR SLOTTING PISTON-RINGS AND SIMILAR OBJECTS.

1,353,558.

Specification of Letters Patent. Patented Sept. 21, 1920.

Application filed November 22, 1919. Serial No. 339,811.

To all whom it may concern:

Be it known that I, MANUEL D. AVILLAR, a citizen of the United States of America, residing at New York city, county of New York, State of New York, have invented certain new and useful Improvements in Machines for Slotting Piston-Rings and Similar Objects, of which the following is a specification.

10 My invention relates to apparatus for cutting diagonal slots in a number of assembled articles, such as a collection of piston rings. In gas and other engines there are employed sets of spring rings seated in 15 circumferential grooves on each piston which rings are discontinuous and press elastically outward against the cylinder walls and so make a practically gas tight joint between the piston and the cylinder in 20 which it reciprocates. One very efficient type of these piston rings has oppositely tapering, overlapping ends which are formed by cutting the original, solid ring blank on a plane sufficiently inclined to the plane of 25 the ring to cause the cut to run from one face or near one face of the ring to the other. Usually the degree of inclination is slight so that the cut extends nearly or quite half way around the circumference of the 30 blank. Heretofore it has been necessary to cut these rings one at a time, but my present invention makes it possible to cut a dozen or any desired number, at one operation. The best form of apparatus at present known to me embodying my invention 35 is illustrated, together with certain modifications, in the accompanying drawings in which—

Figure 1 is a plan view of the apparatus, 40 parts being broken away and others shown in section.

Fig. 2 is a cross section on line 2—2 of Fig. 1.

Fig. 3, is a longitudinal vertical section 45 on the line 3—3 of Fig. 2, parts being broken away.

Fig. 4 is an enlarged detail horizontal section on same plane as Fig. 1, but showing the jaw face cut-away or backed off at its 50 upper half.

Fig. 5 is a side elevation and partial section of a modification in which the cutters are arranged externally of the ring blanks.

Fig. 6 is a vertical cross section on line 55 6—6 of Fig. 5.

Fig. 7 is a perspective view of one of the

ring blanks after it has been slotted and cut, and

Fig. 8 is a similar view after it has been further treated to form a completed piston 60 ring.

Throughout the drawings like reference characters indicate like parts.

The device constituting the particular embodiment of my invention shown in the drawings for purposes of explanation and illustration is a chuck designed to be used as an attachment to an engine lathe, or any suitable form of milling machine, in which lathe or machine the cutting tool may be 65 mounted and operated. To this end the apparatus shown in the drawings is provided with a base 1 which may be conveniently clamped to the tool carrier of a lathe or to the bed or table of a milling machine. 70 At the left hand end of the base (see Figs. 1, 3 and 5) is a housing 2, in which is journaled one end of a swinging chuck 21, while the other end is journaled in the housing 3. This chuck embodies the essential principle 75 of my invention and may be made in any one of many widely varied forms as to details of construction, so long as each of the jaws 4 and 5, has the operative portions of its face located in a plane which is parallel to 80 that of the other jaw, and slightly inclined to the longitudinal axis of the chuck as a whole, and means are provided for holding a series of ring blanks 9 between the jaws so that their centers are in line. When so 85 held in the chuck according to one form of my invention each ring blank will be slightly offset from its neighbor, as best shown in Fig. 4. The means here shown for holding the ring blanks with their 90 centers thus in line comprise one or more justifying bars or surfaces such as 6, 7 and 8, extending from one jaw to the other and parallel to the axis of the chuck, against which bars or surfaces the ring blanks are 95 pressed before being clamped together by jaws 4, and 5. Other means may be devised for accomplishing this result along other lines. If, the inclination of the jaw faces 4 and 5 to any plane perpendicular to 100 the axis of the chuck is equal to the inclination of the desired cut in each piston ring to the plane of that ring, and a series of ring blanks 9, are clamped between the chuck faces with their outer circumferences justified by the surfaces or bars 6, 7, 105 and 8, or by one or more of said bars or

95

100

105

110

equivalent means, it is evident that a series 5 to the axis of the chuck can simultaneously cut the proper slits across all the rings at one operation, if the cutting zone is confined to one side of that chuck diameter which has substantially the maximum angle 10 of inclination to the planes of the clutch jaws.

Various devices for supporting and operating the chuck jaws, and the cutters, as well 15 as for swinging or moving either chuck or cutters so as to obtain the requisite travel of the cutters relative to the rings held by the chuck may be employed.

In the particular arrangement of elements 20 illustrated in Figs. 1, 2 and 3 of the drawings the cutter mandrel 11, extends through the ring blanks 9, so that the cutting is done from the inside outward, and the chuck is 25 swung on its axis to produce the necessary circumferential travel or feed motion of the work around the cutters, which latter rotate 30 on a stationary axis, being supported on the live spindle 30 and tail stock 31, of an ordinary lathe, in the arrangement shown in the drawings. The construction and clamping 35 action of the chuck jaws 4, and 5, as shown in these figures of the drawings, are as follows: The main body of the chuck has a substantially cylindrical end sleeve 12, which is journaled in the housing 2 and held in position 40 by the end nut 13, and keyed into the annular end 32 of the main chuck body 21, by key 25. At the other extremity the chuck body 21 has an annular end 14, into which telescopes the end sleeve 15, the two being 45 prevented from relative rotation by key and keyway 16. The inner end of the telescoping sleeve 15 forms the inclined chuck jaw 5. The other jaw 4 is formed on the inner face of the other sleeve 12. An outer sleeve 50 17, is screwed on to sleeve 15, and journaled in housing 3; being held therein by nut 18. Turning sleeve 17, in one direction will force jaw 5, toward its companion jaw 4. Turning the sleeve in the other direction will force 55 the jaws farther apart and open the chuck. When the jaws are closed on a column of ring blanks 9, they can be locked in that position by setting up jam nut 19, equipped with hexagonal faces as shown in Fig. 1, 55 with which a spanner may engage. Similar hexagonal faces are provided for operating the movable chuck jaw 5, by rotation of sleeve 17.

The swinging motion of the chuck 21, in 60 the journal bearings in housings 2 and 3, is caused and controlled by worm gear 22, formed integral with the chuck and meshing with worm 23, journaled on base 1, and operated by crank 24.

65 The justifying bar 6, is movable on the

chuck body 21, being clamped in different positions of adjustment by screws 26, passing through slots 27, in the chuck body. 28, 29, indicate the slits cut in the ring blanks by cutters 10, and extending from one face of 70 each blank to the other face, or nearly so.

In operation the cutter mandrel 11, is set 75 in the rotating head or live spindle of the lathe or milling machine and the base 1, of my apparatus is clamped to the tool holding 80 table of the lathe or to the work carrying table of the milling machine, in such position that the axis of the chuck is parallel to the axis of the cutter mandrel so that the latter may extend through the chuck and 85 ring blanks held therein. The cutters 10, are as thin as may be consistent with their required strength and are equi-spaced apart a distance equal to the length of a straight line passing through a ring blank from one 90 face to the other at right angles to the plane of the proposed cutting operation, and there is one cutter preferably for each ring blank in the chuck. The ring blanks 9, are assembled in the chuck around the cutter, or 95 the ring blanks are chucked and the cutters inserted afterward. In the chucking operation the justifying bar 6, is forced against the ring blanks so that they are all brought to a bearing on the justifying faces 6, 7 and 8, and they are clamped in that position by the set screws 26. The screw sleeve journal 17, is next turned so as to force the jaw 5, toward jaw 4, until it firmly grips the column of ring blanks 9, against the said 100 opposing jaw 4, and then the jam nut 19, is set up to clamp jaw 5, in this position. This completes the chucking of the blanks.

The planes of jaw faces 4, and 5, are substantially perpendicular to the plane of base 105 1, so that a substantially horizontal diameter of the chuck is the one having the greatest angle of inclination to the jaw faces. The zone of cutting action of saws 10, on ring blanks 9, must be confined to the semicircle 110 above or below this particular horizontal diameter if the slit cut is to run only from one ring face or form a point near such ring face, toward the other. As shown, the cutters are arranged to operate on the upper 115 semicircle. This, as indicated in Fig. 1, produces a diagonal slit in the upper half of each ring cutting it through from one face of the blank to the other, or nearly so.

The assembled ring blanks being held by 120 the chuck jaws in positions slightly inclined to a perpendicular to justifying surface 8, of the chuck, and forced against it by justifying bar 6, are each offset slightly one from the other at their outer edge along 125 their horizontal diameters as best shown in Fig. 4. The zones for cutting or slitting in each ring are thus brought all in line and are in planes perpendicular to the axes of the chuck and of mandrel 11, so that they 130

may all be cut simultaneously by the gang of circular saws 10, mounted on said mandrel. Accordingly when the ring blanks are chucked, as above described, the lathe is set 5 in motion and the tool holder is fed across until the revolving saws 10 have cut through the ring blanks at the ends of their horizontal diameters. The tool holder is then left in that position while crank 24, is turned 10 to slowly swing the chuck on its axis and extend the cutting action around or nearly around the upper half of each ring blank. If the inclination of jaw faces 4 and 5, is correct for the thickness of ring blanks being operated on, the saws will cut slits from 15 one face or from a point near one face of each blank diagonally across to the other face, or nearly to it, and the completed slit rings for piston packing are thereby 20 formed, or may be easily formed therefrom by short cross cuts at the ends of the diagonal slits made after the blanks are taken out of the chuck.

As the saws 10, cut slightly beyond the 25 outer circumferences of the blanks 9, to insure completeness of the cutting action, they may cut into the justifying bar 6, or surface 8, or both, as shown at 29, 29 in Figs. 2 and 4, but as the cuts will always come in 30 the same places, if blanks of the same thickness are used, this will still leave the main portion of the justifying faces uncut and not interfere with the justifying action thereof.

35 In order to make sure that the saws are not pinched by the clamping action of the jaws, the latter may be cut-away slightly or otherwise backed off, along the semi-circle opposite the halves of the ring blanks which 40 are to be slit, as indicated at 20, in Fig. 4.

The back of the chuck which carries the justifying surface 8, may be cutaway above the bearing surface as shown at 38, in Fig. 6. This is especially desirable when the cutters 45 operate externally of the ring blanks as in the modification shown in Figs. 5 and 6. In this construction the chuck 33 and ring blanks held by it do not swing. Said chuck is clamped to the tool carrying table 34 of 50 the lathe while the larger cutters or circular saws 35, are mounted on the mandrel 36 outside the chuck. If the parts are properly proportioned and located the usual horizontal motion of the table produced by crank 55 37 will move the ring blanks under the revolving cutters 35, and produce the desired slits therein.

As this chuck does not swing, its construction may be more simple. Jaw 39 is 60 adjustable endwise in housing 42 and held in adjusted position and prevented from turning by bolt and slot 40. Jaw 41 is movable endwise in housing 43, and is prevented from turning by key 44, and is adjusted in 65 or out by sleeve 45 threaded on its exterior

which sleeve rotates in housing 43, and has an external circumferential groove 46, with which pin 47, set in the housing, engages. Thus the sleeve 45 is free to rotate in housing 43, but cannot move endwise therein. 70 48, is the jam nut for locking jaw 41 in any position of adjustment produced by manipulation of sleeve 45.

In operating this form of the invention, the table 34 and chuck 33 carried by it are 75 moved to the right (looking at Fig. 6) away from the cutters and the ring blanks chucked between jaws 39 and 41. The cutters are then set in rotation and the table 34, moved in the direction of the arrow un- 80 der the cutters as indicated by Fig. 6.

The cut blank produced by the machines of my invention is shown at 49 in Fig. 7, having the slot 28, still open, as formed by the cutter. This is then sprung and heat 85 treated so that it sets with the tapered, overlapping ends in contact as shown in Fig. 8, but this constitutes no part of my invention, being shown merely to make more clear the purpose and method of use of my improved 90 apparatus for producing these rings.

In the forms of apparatus here shown the cutters have no motion of translation or travel, while the chuck does move or travel to make the necessary length of cut around 95 the rings. Evidently a reversed arrangement would produce the same result.

Also, in the modification in which the cutters are large in diameter and operate exteriorly of the rings, the latter need not be 100 chucked so that the line of their centers is at right angles to the planes of rotation of the cutters, so long as the cutters are spaced apart the proper distance for any particular angle of inclination of the line of centers of 105 the rings.

Having described my invention I claim:

1. A chuck for holding a series of articles such as rings designed to be slotted diagonally, which chuck comprises, in combination 110 a frame, two jaws oppositely mounted on said frame so as to be capable of motion toward and from one another along a line parallel to the longitudinal axis of the chuck, and means for producing such motion, each of said jaws having the portions of its face adapted to engage the rings arranged in a plane slightly inclined to the longitudinal axis of the chuck and parallel to the corresponding plane of the face of the 120 other jaw.

2. A structure such as set forth in claim 1, combined with a justifying bar mounted on the frame having its working face parallel to the axis of the chuck and adapted to bear 125 against the outer surfaces of any series of articles clamped between the chuck jaws.

3. A structure such as set forth in claim 1, in which the jaws are annular and adapted to permit the passage of a rotating cutter 130

through the chuck to operate on the inner surface of any rings clamped between the chuck jaws.

4. A structure such as set forth in claim 1 in which the frame is provided with a base adapted to be clamped to the tool carrying table of an engine lathe, and to the work carrying table of a milling machine.

5. A structure such as set forth in claim 1, in which the jaws are revolvably in the frame, and combined with means for swinging said jaws simultaneously and in unison, whereby if any cutting means be brought into action on the article or articles held in the chuck a rotation of the jaws will extend said cutting action circumferentially of the said articles.

6. A chuck for holding a plurality of piston ring blanks, so that they may be uniformly slotted by a plurality of rotary saws mounted on a common arbor, which comprises in combination, a frame having a base-plate adapted to be clamped to the tool carrying table of an engine lathe, a pair of annular jaws mounted and revolvable on said frame about their common axis, the oppositely disposed faces of said jaws being in parallel planes and inclined nearly 90 degrees to the common axis of the jaws, means for moving one of said jaws along the line of said axis and means for rotating both in unison.

7. A combination such as set forth in claim 6 in which the jaw operating means comprise a tubular section telescoping into one end of the chuck body and keyed against rotation therein, the inner end of which tubular section forms the jaw, an exterior sleeve screw threaded on said telescoping section, a journal bearing for said exterior sleeve fixed on the chuck frame, and a second journal bearing for the other jaw, located at the other end of the chuck body both said journals being adapted to prevent endwise movements of the parts immediately supported thereby, whereby on rotating the threaded sleeve on the telescoping section the latter is forced toward or from the other jaw.

8. A combination such as set forth in claim 6 in which the jaw rotating means comprises a connection between the annular

jaws provided with key and keyway engagement permitting endwise motion between said jaws but preventing any rotation of one relative to the other, a worm wheel on one jaw and a worm meshing therewith and journaled on the frame.

9. In a chuck for holding a plurality of piston ring blanks so that they may be simultaneously slotted diagonally by a series of parallel cutters, the combination of a frame provided with two rigid justifying surfaces at right angles one to the other, a justifying bar opposite one face and movable toward and from it, means for clamping said bar against a series of ring blanks resting against the two justifying surfaces, and means for giving all of said blanks a slight, but uniform inclination to a plane perpendicular to one of the justifying surfaces.

10. In a chuck for holding a series of rings for slotting the same the combination of a chuck body and two tubular jaws mounted thereon and movable axially toward and from each other, a slotting tool and means for producing relative motion between the tool and the tubular jaws circumferentially of the jaws, one of said jaws having its face cut away along the arc through which the slotting cutter is arranged to operate.

11. In a machine for slotting a plurality of piston ring blanks at one operation the combination of a plurality of cutters mounted on a revolvable shaft and equi-spaced apart, a chuck having jaws adapted to slide toward and from each other and grasp between them a plurality of ring blanks, means for justifying said blanks in said chuck so that their centers shall all be in one and the same straight line, and means for rotating the cutters and producing a relative motion of translation between cutters and chuck at right angles to the plane of rotation of the cutter, the faces of the chuck jaws being parallel one to another and inclined to the line of said motion of translation at an angle of inclination which the slots in the rings are to have to the faces of said rings.

MANUEL D. AVILLAR.
